The ornamental design for a paddle having an internal reservoir for storage, as shown and described.

DESCRIPTION

FIG. 1 is a perspective view of a paddle having an internal reservoir showing my new design;

FIG. 2 is a front side view, with the back side view being a mirror image thereof;

FIG. 3 is a left side view, with the right side view being a mirror image thereof;

FIG. 4 is a bottom plan view thereof; and,

FIG. 5 is a top plan view thereof.

The broken lines shown illustrate portions of the paddle having an internal reservoir that form no part of the claimed design.
